UNITED STATES PATENT OFFICE

LEE E. ALLEN, OF NEW CASTLE, PENNSYLVANIA, ASSIGNOR TO PENNSYLVANIA ENGINEERING WORKS, OF NEW CASTLE, PENNSYLVANIA, A CORPORATION OF PENNSYLVANIA

HOT METAL MIXER

Application filed June 16, 1928. Serial No. 285,826.

This invention relates to the manufacture of iron and steel, and more particularly to a hot metal mixer adapted to receive and retain hot metal in a molten condition.

5 The present invention relates particularly to a mixer of unusually large capacity and which is designed especially for the purpose of receiving metal from one or more blast furnaces during the time when the mill as a whole is not operating but when the blast furnaces are operating, such for instance, as during the week-end shut-down of the mill. Such a mixer must be capable of receiving and maintaining in a molten condition several hundred tons of metal, the particular installation hereinafter described in detail being designed to hold as much as fifteen hundred tons of metal at one time.

According to the present invention there is provided a mixer designed to receive and retain a large amount of metal with the receiving and pouring spouts so arranged as to secure thorough mixing of the metal and prevent to the greatest possible extent, stagnation at any point in the mixer.

20 A further purpose of the invention is to provide a mixer of large capacity which is firmly braced and which may be easily and conveniently operated.

25 According to the present invention there is also provided a mixer of large capacity wherein the lining for the mixer can be conveniently and easily repaired, or wherein the lining can be removed with a relatively small amount of labor.

These and other objects and advantages are secured by my invention, which may be readily understood by reference to the accompanying drawings showing a preferred embodiment of the invention and in which

Figure 1 is a side elevation of a mixer, part of the structure being shown in vertical section;

Figure 2 is a top plan view of the mixer;

40 Figure 3 is a staggered transverse section in the plane of line III—III of Figure 2;

45 Figure 4 is a detail view showing the cover of one of the receiving spouts and the operating mechanism for the cover;

Figure 5 is a detail view of a portion of the shell of the mixer at one end thereof;

Figure 6 is a more or less schematic view showing a top elevation of the lubricating system for the tipping mechanism for the mixer; and

Figure 7 is a detail sectional view through the operating parts for said mechanism.

In the drawings, 2 designates a foundation on which are supporting standards 3 having a track 4 on the upper face thereof. On each of the tracks 4 is a rocker 5 having a plurality of anti-friction rollers 6 therein.

Resting on the rollers 6 is a hot metal mixer. This mixer has an outer shell 7 which is substantially cylindrical in transverse cross-section below the center thereof, as best shown in Figure 3. As a matter of fact, the shell continues to be cylindrical to a point well above the center line thereof, it being cylindrical clear to the top thereof where the skew backs 8 are located. The ends 9 of the shell are outwardly bowed.

In order to counteract the very heavy loads to which the shell is subjected, it is of heavy construction. It is reinforced with butt-strap 10 on both the sides and the ends thereof. The buttstraps on the cylindrical portion are staggered or alternated with reference to those on the spherical ends, as best shown in Figure 5, and are extended around the corners for additional reinforcement of the connection between the ends and the cylindrical portion of the mixer.

The lining of the mixer is substantially semi-circular to the center line of the mixer. This lining is designated 12. Above the center line of the mixer, which is just below the metal line AA in Figure 3, the sides slope outwardly to a very slight extent to the point where the sides intersect with the roof. This design is of advantage in that there is no overhanging brick which may fall into the mixer in the event that the lining is cut back at the metal line. This outward sloping is also more stable when the mixer is tilted for pouring. The lining is of substantially uniform thickness except in the bottom of the mixer directly under the charging openings, hereinafter described, where the refractories

are made relatively thicker, as indicated at 13 in Figures 1 and 3 for the purpose of resisting the erosive action of the hot metal where it is poured into the mixer.

6 Supported over the top of the mixer is a relatively low flat transversely arched roof 14. This roof is supported along each edge of the cylindrical portion of the mixer on skew blocks 15. The skew blocks 15 set on 10 angle bars 16 secured to the inside of the shell. With this arrangement the entire weight of the roof is supported on the angles 16, and not on the lining 12. This is an important feature of the construction because 15 it makes the roof entirely independent of the lining, and even though the lining becomes badly eroded there is no danger of the roof falling into the mixer.

The shell of the mixer is encircled by a 20 plurality of spaced apart curved beams or rails 17 that engage the rollers 6 on the rocker frames 5. The tops of the rails 17 are connected together by arched beams 18 which serve to hold the top of the mixer from 25 spreading. Due to the fact that the arch of the roof is relatively wide, and relatively flat, roof ties 19 are preferably stretched transversely across the top of the structure, and these can be put under tension by taking 30 up on the eye-bolts 20 at the ends thereof, these eye-bolts being secured to castings mounted on the skew backs 8. These roof ties place the arch under a strain, and there is no possibility of the stresses being reversed 35 when the ladle is tilted for pouring.

In the top 14 at one side of the longitudinal center of the ladle are two charging openings 21. One opening is adjacent each 40 end of the mixer, and the mixer itself is provided with a single pouring spout 22 which is at substantially the center of the mixer. The charging openings are formed of heavy 45 steel castings 23 rigidly tied to the adjacent cross beams 18, the castings serving to connect the cross beams, as clearly shown in Figure 2. Set into each of the castings 23 is a cast thimble or ring 24 having a separate lining 25 therein, as best shown in Figure 4.

By reason of this arrangement the lining 50 at the top of each hole can be quickly replaced when necessary by merely replacing one ring 24 with another ring having a fresh lining 25.

In addition to being tied together by castings 23 the roof is securely braced and the various members 18 tied together by structural braces 26 and by straps 27, as best shown in Figure 2. This bracing is comparatively open so as to allow for sufficient 60 radiation of heat therefrom to protect the refractories of the roof. Each of the charging holes is provided with a cast cover 28 so mounted, as hereinafter described, that it can be swung entirely free of the charging 65 opening. Each cover has a lining 29 therein.

The construction of the cover and the operation thereof may be best understood by reference to Figure 4. The cover 28 has a lug 30 thereon to which the end of a supporting arm 31 is pivotally secured by a pin 32. On the opposite side of the cover is a similar lug 33 having a short slot 34 therein, and a pin 35 on the arm engages in this slot. The arm 31 is pivotally mounted on the casting 23 at 70 36, and the arm is curved to be clear of the cover 28. When the arm 31 is swung upwardly, to the dotted line position shown in Figure 4, the cover 28 is positioned well back of the charging hole and is entirely clear of the hole. This permits metal to be easily 75 poured into the charging hole without the pouring operation being interfered with by the cover. Covers as heretofore constructed have interfered more or less with the charging 80 of the mixer.

For actuating the cover there is provided a link 37. One end of this link is pivotally connected at 38 with the arm 31 between the lugs 30 and 33. The connection between the link 37 and the arm 31 at 38 is preferably one which permits of a slight lost motion between the link and the cover. The other end of the link 37 has a bifurcated end portion 39 engaging a bearing block 39^a on a crank 40 at the end of a crank arm 41. Shims may be provided at each side of the bearing block 39 as shown to permit of a slight adjustment of the link 37 longitudinally relatively to the crank pin 40. The crank arm 41 is keyed to a shaft 42 mounted on the top of the mixer. The shaft 42 is driven from a reversible motor 43 through a reducing gear 44, as shown in Figure 2.

When the motor 43 is operated with the parts in the full line position shown in Figure 4, the shaft 42 is rotated through an arc to swing the crank arm 41, as indicated by the broken lines in Figure 4. As the crank arm 41 swings, it pulls the link 37 to the right, as viewed in Figure 4, swinging the cover to the open position shown. Due to the slight lost motion between the link and the cover at 38 the dead center relation of the shaft 42, the crank pin 40 and the connection 38 can be overcome.

For closing the charging hole the motor 43 is driven in the opposite direction whereupon the link 37 pushes the cover down. Due to the fact that the cover 28 has a floating connection on the arm 31 due to the pivot 120 32 and the pin and slot arrangement 34-35, the cover can adjust itself to any irregularity on the surface of the link 25 without damage to the parts.

It will be noted that the cover and all of its operating mechanism is mounted directly on the mixer, and the operation for both opening and closing each cover is positive. Door operating mechanisms as heretofore provided have generally required the use of cables at- 125 130

attached to operating means not mounted on the nuts 62 operate in a bath of oil. By reason of the mixer, so that when the mixer is tilted some of the cover plate 51 the bil may be kept in a compensating movement for the cables must be relatively clean. Any dirt which accumulates is provided. Furthermore, the arrangement in the troughs tends to fall to the bottom as heretofore generally used did not provide for any positive closing of the door, it being necessary to initially push the door and nut along the trough. At each end of the trough is a depression 70, as best shown in

Figure 6. Leading from the depressions or the link 37 and the parts with which it coop-packets 70 are pipes 71 that communicate with the charge door with a central pipe 72 leading to a pump 73 to swing open by gravity when the ladle is operated by a motor 74.

Due to the dead center relation between the parts with which it coop-packets 70 are pipes 71 that communicate with the charge door with a central pipe 72 leading to a pump 73 to swing open by gravity when the ladle is operated by a motor 74.

15 Platforms and walks are provided on top through the filter 76 the clean oil is returned of the mixer to provide convenient access for through a pipe 77 having branches 78, one of the making of repairs, and the platform is which leads to each of the troughs 50 and is provided at each end with safety ladders 45 charges into these troughs intermediate the as illustrated.

20 Located under the mixer at each side of the troughs. With this arrangement the oil in the pouring spout is a trough 50 having a cover other troughs can be continuously circulated thereover, this cover having parallel slots and filtered, thereby keeping the oil clean therein. The troughs extend transversely and the troughs relatively free from any accumulation of scale, mill dust and the like.

25 (d) One feature of considerable advantage in the length of the trough is a screw 53. This screw is formed on a shaft 54, best shown in this mixer is the provision of the charging Figure 3, one end of which is supported in holes adjacent each end of the mixer with a bearing 55 in one end of the trough. Then a single pouring spout at the middle of the other end of the shaft 54 passes through a mixer and on the opposite side. As previously

30 gland 56 and has a driving gear 57 on its outer end that meshes with a bevel gear 58 on the outer end that meshes with a bevel gear 58 on a cross shaft 59. The cross shaft 59 is a large amount of molten metal. If there are arranged to rotate the gears 57 at the end of a shaft, but a single charging opening directly 35 each trough, and at each end of the shaft 59 opposite the pouring opening, the freshly is a driving motor 60. The motors 60 are charged metal would flow straight across the designed to be operated in unison, but either mixer and out the pouring spout, and the motor alone is capable of tilting the mixer metal at the ends of the mixer would become 40 through the operation of the screw mechanism relatively stagnant and become cooler.

45 (e) In case the other motor is for any reason, inoperative. Likewise if the charging opening were at one end of the mixer and the spout at the outer end that meshes with a bevel gear 58 on a cross shaft 59. The cross shaft 59 is a large amount of molten metal. If there are arranged to rotate the gears 57 at the end of a shaft, but a single charging opening directly 45 each trough, and at each end of the shaft 59 opposite the pouring opening, the freshly is a driving motor 60. The motors 60 are charged metal would flow straight across the designed to be operated in unison, but either mixer and out the pouring spout, and the motor alone is capable of tilting the mixer metal at the ends of the mixer would become 50 through the operation of the screw mechanism relatively stagnant and become cooler.

55 (f) On the bottom of each trough 50 is a guideway 61. On the screw 53 is a nut 62 to flow in a straight channel from one end of the screw 53 to the other, and the metal at each end of the guideway 61. The nut 62 is side of the middle tends to become stagnant.

60 (g) preferably provided with a removable cover. With the present arrangement metal can be charged alternately into opposite ends of the nut 62 for inspection to see when the metal tends to keep the metal at the nut is worn to such an extent that replacement of the mixer highly heated and present is necessary. Projecting from each end fitting stagnation of the metal in the ends.

65 (h) side of the nut 62 is a trunnion 65. Connected with the trunnions 65 are links 66 both ends to the spout. Stagnation of the metal at any point is thereby prevented and connected at 67 to castings 68 secured to the metal is more thoroughly mixed than in bottom of the mixer.

70 (i) structures of this nature heretofore provided. With the parts in the position shown in Figure 3 the shafts 54 may be rotated to apply heat to the metal by means of burners cause the nuts 62 to travel to the left as at each end of the mixer above the top of the viewed in this figure. The links 66 impart metal. In order to effectively heat the metal a tilting motion to the mixer which is desirable that as large a surface as possible the rockers 5. The pouring spout 22 is thus liable to be exposed to the flames. A relatively 75 tipped downwardly so that metal can be poured into a wide flat arch of the present invention gives a pour into a ladle B. By reversing the direction of rotation of the shafts 54 the mixer larger area over the surface of the metal can be righted.

80 The wide flat arch is relatively close to the The wide flat arch is relatively close to the top of the metal, and provides a large sur-

85 face of the metal, and provides a large surface of the metal, and provides a large sur-

90 face of the metal, and provides a large surface of the metal, and provides a large sur-

face for radiating heat absorbed from the combustion of fuel to the metal. The mixer is therefore highly efficient in enabling the large body of metal therein to be kept at the desired temperature.

The top of the mixer and the parts supported thereon are entirely independent of the body of the mixer so that when it is necessary to reline the mixer the entire top can be lifted off with cranes without breaking the refractories in the top of the mixer. Due to the outward slope of the refractory walls above the line AA, the refractories can be broken into large pieces and removed with comparative ease after the top of the mixer has been removed, which is not the case with the usual mixer, of the fully cylindrical mixer.

The spherical shape of the ends throws the refractories in the ends in compression in every direction so that the ends of the mixer are strong and well able to resist the pressure to which they are subjected.

The removable rings in the charging holes enable the refractories around the charging holes to be kept in a good state of repair notwithstanding the fact that they are frequently subjected to the erosive action of hot metal poured directly thereon and notwithstanding the fact that metal will freeze thereon.

The arrangement of the doors whereby they may adjust themselves to irregularities at the surface of the charging holes, and the novel arrangement of the doors and the operating mechanism therefor is of considerable advantage as hereinbefore pointed out.

Certain features of the ladle construction are claimed in my respective copending applications Serial Nos. 384,389 and 384,390, filed August 8, 1929, each of which is a division of this application.

While I have illustrated and described a particular embodiment of my invention, it will be understood that this is merely by way of illustration and that various changes and modifications may be made in the construction shown within the contemplation of my invention and under the scope of the following claims.

I claim:

1. In a hot metal mixer, a ladle supported for tipping, having a body portion comprised of a metal shell and a refractory lining, the body portion of the ladle being substantially semi-circular in transverse cross section throughout the entire length of the mixer below the longitudinal axis thereof, and an arched top supported on the top of the shell independently of the lining, said shell having supporting means on the inside thereof on which the top is supported, said supporting means being set back sufficiently to enable the lining to be lifted clear thereof.

2. In a hot metal mixer, a ladle supported

for tipping having an elongated body portion comprised of a metal shell and a refractory lining, the body portion being substantially semi-circular in transverse cross section throughout the length of the mixer below the longitudinal axis thereof, the shell and the lining extending below the plane of the longitudinal axis of the mixer, the inner face of the lining above the plane of the longitudinal axis being substantially straight, and a cover supported on the shell along each longitudinal edge thereof, said shell having supporting means on the inside thereof on which the top is supported, said supporting means being set back sufficiently to enable the lining to be lifted clear thereof.

3. In a hot metal mixer, a ladle supported for tipping having an elongated body portion comprised of a shell and a lining, said body portion being substantially semi-circular in transverse cross section below the longitudinal axis thereof, the sides of the ladle extending a relatively short distance above the plane of the longitudinal axis, these portions of the sides being sufficiently straight, cover supporting means on the inside of the shell adjacent the upper longitudinal edges thereof and set back sufficiently to be clear of the lining, and an arched top supported substantially entirely on said cover supporting means.

4. In a hot metal mixer, a ladle supported for tipping comprised of a shell and a lining, the body of the ladle being elongated with the portion thereof below the longitudinal axis thereof substantially semi-circular, a cover over the top of the body, rails encircling the shell at intervals along the body, beams over the cover connecting the ends of the rails, rockers engaging the rails, the cover being arched and being supported on the upper edges of the shell, and roof ties extending across the top for placing the cover under strain.

5. In a hot metal mixer, a ladle supported for tipping comprised of a shell and a lining, said ladle having an elongated body portion which is substantially semi-circular in cross section below the longitudinal axis thereof, rails encircling the body at intervals along the length thereof, rockers engaging the rails, an arched cover for the ladle, beams extending across the top of the cover connecting opposite ends of the rails, said cover having charging holes therein, and a casting surrounding each charging hole rigidly connecting two of said beams.

6. In a hot metal mixer, a ladle supported for tipping comprised of a shell and a lining, said ladle having an elongated body portion which is substantially semi-circular in cross section below the longitudinal axis thereof, rails encircling the body at intervals along the length thereof, rockers engaging the rails, an arched cover for the ladle, beams extending

across the top of the cover connecting opposite ends of the rails, said cover having charging holes therein, a casting surrounding each charging hole rigidly connecting two of said beams, and structural bracing members between the beams rigidly connecting them together.

7. In a hot metal mixer, a ladle supported for tipping comprised of a shell and a lining, said ladle having an elongated body portion which is substantially semi-circular in cross section below the longitudinal axis thereof, rails encircling the body at intervals along the length thereof, rockers engaging the rails, an arched cover for the ladle, beams extending across the top of the cover connecting opposite ends of the rails, said cover having charging holes therein, a casting surrounding each charging hole rigidly connecting two of said beams, and roof ties extending across the top of the ladle and secured to each side of the shell thereof for putting the arched cover under strain.

8. In a hot metal mixer for the mixing and storing of at least several hundred tons of molten metal, a foundation, rockers carried on the foundation, an elongated ladle carried on the rockers the lower portion of which is substantially cylindrical in transverse cross-section, said ladle having a covered top, said ladle having a charging opening in the top thereof at each side of the transverse center of the receptacle, and a single pouring spout at one side of the receptacle approximately midway between the two charging openings whereby metal may be charged into opposite ends of the mixer and flow from each end toward the center.

In testimony whereof I have hereunto set
40 my hand.

LEE E. ALLEN.
